CLAIM

The ornamental design for a decoration, as shown and described.

DESCRIPTION

FIG. 1 is a perspective front view of a decoration embodying the new design, according to one embodiment;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof.

FIG. 8 is a perspective front view of a decoration embodying the new design, according to another embodiment;

FIG. 9 is a front view thereof;

FIG. 10 is a rear view thereof;

FIG. 11 is a left side view thereof;

FIG. 12 is a right side view thereof;

FIG. 13 is a top view thereof; and

FIG. 14 is a bottom view thereof.

FIG. 15 is a perspective front view of a decoration embodying the new design, according to another embodiment;

FIG. 16 is a front view thereof;

FIG. 17 is a rear view thereof;

FIG. 18 is a left side view thereof;

FIG. 19 is a right side view thereof;

FIG. 20 is a top view thereof; and

FIG. 21 is a bottom view thereof.

FIG. 22 is a front view of a decoration embodying the new design, according to another embodiment;

FIG. 23 is a rear view thereof;

FIG. 24 is a left side view thereof;

FIG. 25 is a right side view thereof;

FIG. 26 is a top view thereof; and

FIG. 27 is a bottom view thereof.

FIG. 28 is a front view of a decoration embodying the new design, according to another embodiment;

FIG. 29 is a rear view thereof;

FIG. 30 is a left side view thereof;

FIG. 31 is a right side view thereof;

FIG. 32 is a top view thereof; and,

FIG. 33 is a bottom view thereof.

Broken lines are used to illustrate portions of the decoration that form no part of the claimed design. The appearance of any portion of the article between the break lines forms no part of the claimed design.

(Continued)

The decoration can be a party decoration (e.g., for birthdays, holidays, special occasions), and for example can be inserted in cakes and gifts (e.g., flower pots).
